(57) **CLAIM**

The ornamental design for a hair clip packaging cardboard, as shown and described.

DESCRIPTION

FIG. 1 is a front perspective view of a hair clip packaging cardboard, showing my new design;

FIG. 2 is a front perspective view thereof;

FIG. 3 is a rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a perspective view thereof in an unfolded state; and,

FIG. 11 is a perspective view thereof in a condition of use. The broken lines in the drawings illustrate the portions of the hair clip packaging cardboard, which form no part of the claimed design.

The additional broken lines shown in FIG. 11, depict environmental structure only and form no part of the claimed design.

1 Claim, 11 Drawing Sheets
